UNITED STATES PATENT OFFICE.

FRANK E. MARCY, OF SALT LAKE CITY, UTAH.

TUBE-MILL.

1,226,555.

Specification of Letters Patent.

Patented May 15, 1917.

Application filed January 18, 1917. Serial No. 143,077.

To all whom it may concern:

Be it known that I, FRANK E. MARCY, a citizen of the United States, residing at Salt Lake City, in the county of Salt Lake and State of Utah, have invented certain new and useful Improvements in Tube-Mills, of which the following is a full, clear, and exact description, reference being had to the accompanying drawings, forming a part hereof.

My invention has relation to improvements in tube mills; and it consists in the novel features of construction more fully set forth in the specification and pointed out in the claims.

The present invention is primarily directed to that feature of the mill known as the screen-grate, that is to say, the transverse perforated diaphragm interposed between the crushing compartment or chamber of the mill and the discharge head, and secondarily to the wall liner on which the life of the grate and feed-end liner are in a measure dependent. The invention has for its object, to provide special means for securing the grate in position without regard to the detailed construction of the grate, such securing means being applicable to a cast grate, to one composed of rolled bars welded or not welded, to a grate composed of spirally disposed bars, to one having its bars disposed radially or parallel to the chords of the circular cross-section of the shell of the mill, or to a grate having its bars disposed in any other manner known to the art. A further object is to provide special means for anchoring the member inclosing and carrying the grate, to the shell of the mill; to provide means affording facilities of renewing worn out grates. A further object is to provide a wall liner which will permit the balls or other grinding bodies employed in the crushing compartment to so roll down the liner during the rotation of the mill as not to impinge destructively against the grate (and feed-end liner) thereby avoiding pockets and holes in the grate; and finally, to provide further and other features of construction the advantages of which will be readily apparent from the following detailed description of the invention in connection with the accompanying drawings in which—

Figure 1 represents a side elevation of the mill with parts in section, a portion of the shell being removed; Fig. 2 is a plan of the inclosing ring for the grate showing in plan

one-half of the grate in position within the ring, the view being taken from the side facing the radial lifters of the discharge head against which the outer face of the grate bears, three of the lifters (there are six in the present mill) being shown outlined by dotted lines in the space from which the grate has been removed to show their disposition relatively to the ring and grate when the parts are assembled; Fig. 3 is a half transverse section and edge view of the grate and its inclosing ring on the zig-zag line 3—3 of Fig. 2; Fig. 4 is an enlarged cross-section through the discharge head and two of the radial lifters and through the grate, on the line 4—4 of Fig. 1; Fig. 5 is an inner face view of a portion of the discharge head and its lifters; Fig. 6 is an end view of one of the wall-liner sections; Fig. 7 is an inner plan or face view of one of the wall liner sections; Fig. 8 is a perspective of one of the grate bars with portion broken away; Fig. 9 is a view similar to Fig. 2 showing a grate composed of rolled bars welded together; Fig. 10 is a cross-section on the line 10—10 of Fig. 9; Fig. 11 is a perspective of one of the rolled bars with portion broken away; Fig. 12 is an end view of a modified form of wall-liner section; and Fig. 13 is an inside plan thereof, portion being broken away.

Referring to the drawings, and for the present to Figs. 1 to 8 inclusive, 1 represents the outer shell of the crushing compartment of a cylindrical container, drum, tumbling barrel or equivalent tubular member, the same being provided with a suitable wall liner 2 and a feed-end liner 2'. The feed-end head 3 of the mill is provided with the hollow feed-trunnion 4, the discharge-end head 3' being provided with the hollow discharge trunnion 5 as well understood in the art. Formed on the inner face of the discharge-head 3' are a series of radial blades or lifters 6 against which the grate is adapted to bear when the latter with its inclosing ring is properly mounted within the mill. In the present embodiment of my invention six lifters 6 are employed (though I am not restricted to the actual number employed) said lifters being T-shaped in cross-section as shown (Fig. 4), the flanges of the lifters directly affording a rest for the grate bars. In the present construction the entire shell of the drum comprises the large section 1 carrying the feed-head 3, and the rela-

tively smaller section 1' carrying the discharge-head 3', the two sections being bolted to one another along the flanges a , a' , of the respective sections, the smaller section carrying the drive 7. The grate-supporting faces of the radial lifters, that is to say the faces of the flanges of the lifters are disposed in the plane of the annular ledge 8 projecting from the inner walls of the shell-section 1', said ledge being removed a suitable distance from the flanged terminal of said section. The wall liner 2 terminates at the flanged terminal of the section 1, so that when the shell sections are assembled, there is left an annular space between the ledge 8 and the adjacent terminal of the wall liner 2 to accommodate the grate-inclosing and supporting ring 9, the details of which are fully shown in Figs. 1, 2, and 3. This ring is L-shaped in cross-section, that is to say the ring is provided with an inwardly turned flange h (Fig. 3) on the inner face of which the grate bars 10 composing the grate are initially deposited, the depth of the bars being slightly in excess of the width of the inner annular face of the ring (Fig. 3) so that the grate projects a slight distance beyond the ring to engage the radial lifters 6 and ledge 8, between which and the flange h the grate is held confined when the parts are assembled (Fig. 1). The bars 10 are cast bars and are formed with suitable spacing lugs d to properly space the bars. At diametrically opposite points the ring 9 is provided with flat sections or portions m for the accommodation of suitable set screws 11 by which the grate-bars are firmly and sufficiently driven against one another and frictionally held in the ring to permit the ring and grate to be deposited as a unit within the shell section 1' before the latter is bolted to the section 1. At diametrically opposite points, and removed ninety degrees from the flat portions m , the periphery of the ring 9 is provided with recesses t (open at one end only) with which engage suitable lugs 12 formed on the inner wall of the shell section 1', said lugs 12 and recesses t locking the ring against rotary displacement when once deposited in position in the mill. In addition, the section 1' is tapped circumferentially at intervals for the reception of set screws 13 which operate to tightly clamp the ring 9 in position and hold the same against possible movement in any direction.

In mills where a transverse grate or diaphragm is disposed in the manner here shown there necessarily are formed two distinct compartments within the mill, to wit, a crushing compartment C, and a finishing compartment C', the first compartment being on one side of the grate, and the second on the opposite side, the lifters 6 being located in said finishing compartment and di-

viding the same into a series of radial sub-compartments from which the finished product is discharged into the trunnion 5, the usual discharge cone 14 directing the material into said trunnion.

The operation hardly calls for any description but briefly stated is as follows: The material is fed to the mill through the hollow trunnion 4 into the crushing compartment C, where it is ground during the rotation of the mill about its axis, the fine particles passing through the screen-grate composed of the bars 10 (or their equivalents) and entering the radial sub-compartments formed by the lifters 6 in the finishing compartment C' (between the grate and the head 3'), whence the finished product passes out through the trunnion 5 to any suitable point for further treatment. The coarse particles which cannot pass through the grate remain in the crushing compartment until sufficiently reduced in size.

In the grate above described the several bars were held together by friction, but in the modification shown in Figs. 9 and 10 additional means for holding the bars 10' together are provided in the shape of welds w between the spacing lugs d' , but extending only partially the depth of the bar, no change being made however in the ring 9 by which the grate is supported. Again, the bars instead of being cast may be rolled, the roller bar 10" preferably assuming a shape on the order shown in the modification in Fig. 11, the spacing lugs d'' being rolled as a part of the original bar from which the bars forming the grate are subsequently cut off. It is apparent that the invention herein is susceptible of a large variety of modifications both in the grate and supporting ring therefor, and likewise in the discharge head and lifters thereof, and it is therefore unnecessary to adhere to the forms here shown to be within the spirit of my invention. Thus in the ring 9, the support for the grate need not necessarily be a "flange" such as h , but may be any suitable ledge or support properly disposed on the ring to serve its purpose. The ring 9 is not absolutely indispensable as other means might be improvised by the skilled mechanic to maintain the grate in position without departing from the spirit of my invention.

As pointed out above, one of the objects sought by the present invention is to prevent the disintegration of the grate by the impact of the balls rolling down the wall liner 2 with the rotation of the mill. These liners as well understood in the art are provided with lifters, corrugations, or ribs r for lifting the balls and material through a certain arc of the mill's rotation, the balls when released upon reaching their highest point rolling down the incline formed by the contents of the mill to be again lifted

and subsequently released as fully understood in the art. Where the lifters extend the full length of the wall-liner, the balls tend to dig holes or pockets in the grate 5 (and feed-end liner) the holes corresponding in number to the number of lifters. By terminating these lifters (be they ribs or corrugations) a short distance from the ends of the liner a race-way b is left beyond the 10 terminal of the lifter or rib, the balls freely rolling down this race-way and not seriously impinging against the grate (or end liner). The pockets and holes resulting from the use of full length lifters are thus 15 avoided, and the life of the grate (as well as of the feed-end liner 2') is materially prolonged. The wall liner is preferably built up of longitudinal sections 20, 20, (Figs. 6, 7), the metal tapering from the 20 rib r to the edge of the section, said edge being interposed between the ribbed side of an adjacent section and the shell 1, the parts being secured by rivets, bolts or any equivalent way known to the art. At the ends e , 25 that is, beyond the terminals of the ribs, the metal is preferably of substantially uniform thickness, the weight of metal however at the ends being substantially equal to that of the metal in any other portion of the liner 30 having the same length. By therefore terminating the lifters r a short distance from the grate (and feed-end liner) a ball race b is formed between the lifter terminal and grate contiguous thereto, through which 35 race the balls will roll without damaging the grate. The lifters need not of course be integral with the liner sections. In Figs. 12 and 13 I show a modified liner section 20' having a central lifter r' the same operating 40 as the abbreviated lifter r previously described. In this modification the longitudinal edges of the several sections 20' are placed in abutting relation.

Having described my invention what I 45 claim is:

1. In combination with a drum rotatable about a fixed axis and provided with a head having a central opening for the passage of the material, a series of radial blades or 50 lifters disposed on the inner surface of said head around said opening, a grate, and a one-

piece ring encompassing and having means for holding the grate and operating to maintain the same in proximity to the lifters.

2. In combination with a drum rotatable 55 about a fixed axis and provided with a head having an opening for the passage of the material, a series of radial blades or lifters disposed on the inner surface of the head around said opening, a grate, a ring in the 60 drum provided with a flange for engaging the grate, the latter being positioned between the lifters and said flange.

3. In combination with the peripheral walls of a tube mill provided with suitable 65 lugs extending toward the axis of the mill, a flanged one-piece grate-holding ring provided with peripheral recesses for engaging said lugs, thereby preventing rotary displacement of the ring. 70

4. In a mill of the character described, a suitable ring, a ledge or flange formed thereon, a series of grate-bars deposited on the flange, and means on the ring for driving the bars into firm frictional engagement 75 with one another whereby the ring and bars may be handled as a unit.

5. In a mill of the character described, a grate comprising a series of bars, spacing 80 lugs on the bars for maintaining the bars fixed distances apart, a one-piece supporting member provided with means for frictionally holding the bars together, said member being insertible into the shell of the mill, and means on the shell for locking the 85 member to the shell.

6. In a mill of the character described, a shell section provided with a head, radial lifters disposed on the inner face of the head, a ledge leading from the inner walls 90 of the shell and forming the outer boundary of the lifters, a ring mounted in the shell-section in proximity to the lifters, means for locking the ring to the shell, and a grate carried by the ring and engaging the lifters 95 and ledge aforesaid.

In testimony whereof I affix my signature, in presence of two witnesses.

FRANK E. MARCY.
